ELECTRIC WALL OUTLET AND PLUG
THEREFOR

Wallace H. Lavoie, Hartford, Conn.

Application January 5, 1945, Serial No. 571,379

5 Claims. (Cl. 173—330)

1

This invention relates to an electric wall outlet, and plug therefor.

A primary object of this invention is the provision of an improved electric wall outlet, and a plug to be utilized in association therewith, so arranged as to provide a ready four-way connection for a plurality of plugs.

An additional object of this invention is the provision of such an outlet wherein the plug may be inserted without hesitation or difficulty, even though the outlet be in darkness or in an inaccessible spot.

An additional object of the invention resides in the provision of a plug and outlet wherein the plug will not be enabled to loosen, due to accidental pull thereon.

Still another object of the invention is the provision of such a plug provided with improved contact means whereby the circuit is maintained steadily and efficiently at all times.

A still further object is the provision of means adapted to be utilized in conjunction with either such an outlet or plug, whereby the same may be connected with a conventional opposite outlet or plug.

Still other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a top plan view of the assembled wall outlet.

Figure 2 is a top plan view of the top plate for the outlet.

Figure 3 is a top plan view of the base plate of the outlet.

Figure 4 is a sectional view taken substantially along the line 4—4 of Figure 1.

Figure 5 is a perspective view of the plug adapted to be utilized in conjunction with the outlet.

Figure 6 is a perspective view of the same plug shown in a different position to clarify certain details of construction.

Figure 7 is a side elevational view of an adapter unit, for the purpose of utilizing the outlet of the instant invention in conjunction with a conventional plug, certain parts thereof being shown in dotted lines.

Figure 8 is a top plan view of the unit shown in Figure 7.

Figure 9 is a top plan view of an adapter designed to convert a conventional wall outlet for use with a plug of the instant invention.

2

Figure 10 is a top plan view of an additional section of the unit shown in Figure 9.

Figure 11 is a side sectional view of the combined unit shown in plan in Figures 9 and 10.

Like reference numerals refer to like parts throughout the several views of the drawings.

Having reference now to the drawings, there is generally indicated at 10 a top plate, comprised of a rectangular, or other desired shaped, sheet of metal, plastic or the like, provided with a centrally disposed aperture 11 having a beveled edge 12 and a plurality of radially extending slotted apertures 13 extending at right angles to each other from the aperture 11. Surrounding the slots 13 are bosses 14, for a purpose to be more fully described hereinafter. Underlying plate 10 is a second plate 15, of similar configuration, provided with raised arcuate bosses 16 adapted to underly the central aperture 11 of plate 10, and radially disposed bosses 17, adapted to extend upwardly through the slotted apertures 13, and to the extremities thereof. Positioned on opposite sides of each of bosses 17 are contacts 18, held in position as by screws or rivets 19, and in electrical association in any desired manner with a desired power source.

In assembling the unit, the top plate is adapted to be secured on base plate 15 in any desired manner, as by screws 20 engaging in suitable threaded apertures in the base plate.

Having reference now to the plug adapted to be utilized in the assembly, the same is comprised of a hard rubber or similar circular disk 25, formed at its outer surface with a transversely extending flange 26 of arcuate configuration. Two contact members 27 extend from the interior of the disk 25 and are comprised of extending portions having outwardly flared right angularly disposed extremities 28. Contacts 27 are in electrical association in any desired conventional manner with an outlet cord 29 adapted to lead any desired electrical appliance. The arrangement is such that the flange 26 is in longitudinal alignment with the outwardly flared portions 28, 45 in such manner as to indicate the position thereof to the user of the plug.

From the foregoing the operation of the device should now be readily understandable. When it is desired to insert a plug in the electrical wall outlet, the contacts thereof are merely placed in the central aperture 11 and passed on opposite sides of a boss 17, the lower surface of the disk 25 riding on the associated boss 14, whereupon contact is made between the contact flanges 28 and the contacts 18 to establish an

electrical circuit. Obviously, accidental dislodgement of the plugs and their associated slots as by a pull or tug on the cord 29 is precluded, disengagement being possible only by longitudinal sliding of the plug member. It will correspondingly be seen that four plugs may be associated with the four slots 13 and their associated contacts to provide a plurality of electrical wall outlets.

Adapter means are provided for utilizing a wall outlet constructed in accordance with this inventive concept in conjunction with the ordinary two-pronged plug now commonly associated with electrical fixtures. Such means take the form of a cylindrical plug 35, as best shown in Figures 7 and 8, provided with two apertures 36 adapted to accommodate the contact members of a conventional plug, the plug body having a recess therein 37 within which are positioned contact members 38 terminating in projecting portions 39 flared outwardly as at 40, in such manner as to accommodate the wall outlet of the instant invention.

Similarly, an adapter plug is provided whereby the plug of the instant invention may be utilized in conjunction with the conventional wall outlet.

Such means take the form, as best shown in Figures 9 to 11, of a disk 40 provided with a longitudinally extending aperture 41 beveled as at 42 and provided with a central aperture 43, adapted to be secured as by screws or the like 44 to a second member 45 comprised of a recessed central portion 46 having a pair of arcuate contact members 47 therein in electrical association as by screws or rivets 48 with a pair of vertically extending contact members 49. Bosses 50 serve as stops for the contact blades. Thus it will be seen that when the contacts 28 of a plug in accordance with the instant invention are inserted in the slots 41 and the device rotated ninety degrees, such rotation being permitted by the central aperture 43, the flared portions 28 are engaged under the contacts 47, and electrical contact with the projecting members 49 established.

Now from the foregoing it will be seen that there is herein provided a device accomplishing all the objects of this invention and others including many advantages of great practical utility and commercial importance.

As many embodiments may be made of this

inventive concept, and as many modifications may be made in the embodiments hereinbefore shown and described, it is to be understood that all matter herein is to be interpreted merely as illustrative and not in a limiting sense.

5 I claim:

1. An outlet plug assembly comprising a base plate, a plurality of pairs of spaced contacts secured thereto, an insulating boss between the contacts of each pair, a cover plate secured in spaced relation to said base plate, said cover plate having a plurality of slots overlying said bosses, the cover plate adjacent said slots overlying said pairs of contacts, said bosses extending medially through said slots, said slots opening into an aperture in said cover, and a plug having flanged, depending spaced contacts insertable into said aperture and selectively engageable with said pairs of spaced contacts, said plug contacts underlying said cover and resting upon said spaced contacts.

10 2. The combination of claim 1 wherein said base plate includes upstanding arcuate bosses underlying the periphery of said aperture and engaging the undersurface of said cover plate.

15 3. The combination of claim 2 wherein said arcuate bosses terminate at the edges of adjacent slots.

20 4. The combination of claim 3 wherein said pairs of contacts, said bosses and said slots are disposed radially of said aperture.

25 5. The combination of claim 4 wherein each contact of said pairs of contacts has a bottom portion secured to said base plate and an integral top portion overlying said bottom portion and yieldingly biased towards the undersurface of said cover.

WALLACE H. LAVOIE.
